JOHN K. RHODES, OF BROOKLYN, NEW YORK, ASSIGNOR TO KELLEY MONROE TURNER,
OF JAMAICA, NEW YORK.

TELEPHONIC TRANSMITTING APPLIANCE.

1,039,443.

Specification of Letters Patent. Patented Sept. 24, 1912.

Application filed April 6, 1912. Serial No. 688,861.

To all whom it may concern:

Be it known that I, JOHN K. RHODES, a citizen of the United States, and a resident of Brooklyn, in the county of Kings and 5 State of New York, have invented certain new and useful Improvements in a Telephonic Transmitting Appliance, of which the following is a specification.

This invention relates to telephonic apparatus for the deaf and specifically to a transmitting appliance to be worn as an attachment to the clothing or apparel.

Telephonic service for deaf persons should be adapted to loud voices and soft voices 10 and to near and far conditions, so that it is not possible to dispense with considerable delicate apparatus such as has formed the subject of various prior patents in this branch of the art. The popular taste is, 15 however, against bulky and apparently complicated apparatus as an attachment to personal apparel, and deaf persons are sensitive to appliances which give them a switch-board appearance. Accordingly at- 20 tempts have been made to combine a telephonic transmitter of great sensitiveness with an apparatus for regulating the sensitiveness so as to suit all conditions of practice, and yet make the outfit simple in ap- 25 pearance and not suggestive of electrical switch-board apparatus. The present in- 30 vention provides an improved apparatus of this character.

In the drawings,—Figure 1, is a front 35 view partly broken away of a telephonic transmitting implement embodying the principles of this invention; Fig. 2, is a rear view, and Fig. 3, is a sectional view showing a detail.

Constructions embodying the invention 40 will primarily include a casing 1, the front of which is plain except for a plurality of sound openings 2 as illustrated, and in order to get the great sensitiveness which is to re- 45 produce the faintest sounds, two transmitters 3 of the general type set forth in the patent to Haff 874,004 or Hyde 711,974 are grouped side by side so that they almost touch. This provides substantially as great 50 sensitiveness as with two separate complete transmitting appliances of single transmitter type, and at the same time obtains a compact arrangement. The general result is that the oval character of the instrument 55 permits it to hang down when attached for

example to the edge of a coat pocket, but it does not hang down so far as to vibrate with any pendulum effect which would be objectionable. The edge of the back of the instrument has a deep bevel or chamber 5 60 which produces an interior configuration which co-operates in the sound producing functions and also gives the instrument a much thinner appearance than it would otherwise have. 65

The means for toning down the extreme sensitiveness of the instrument constitutes an important and distinctive feature of the invention in the fact that it occupies interiorly a space which is available without 70 diminishing the efficiency of the operation on the one hand or increasing the bulk on the other. Besides this the regulating means occupies exteriorly a position which is entirely concealed, but which is as accessible 75 to hand manipulation as possible, being in fact so located as to be readily grasped by the hand.

Reference has been made to the fact that the bottom of the instrument as well as the 80 top is semi-circular. Also to the fact that directly inside of this semi-circular bottom of the instrument there is an annular space 4. Constructions embodying the invention 85 will therefore include a plurality of resistance coils in the annular space 4 just mentioned, arranged in series between studs 6 which project through the rear of the casing in an arcuate formation 7 generally 90 corresponding to the shape of the instrument at this end and also to the shape of the internal cavity 4 the studs occupying perhaps about 120 degrees of angular extent. There is also a switch arm 8 which 95 is centrally pivoted at 9 and swings over the contacts mentioned. The extremity of this arm will project and be turned upward in order to provide for convenient manipulation of the resistance arm which can be swung through its entire range by an 100 easy engagement of the fingers, on account of the fact that its movement is generally parallel to the edge of the instrument, and equally accessible in all directions, or sub- 105 stantially so. In Figs. 1 and 2 the switch arm pivot 9 is not exactly concentric with the edge and with the central conical stud 10, but in Fig. 3 a construction is illustrated 110 by which the conical stud 10¹ may be made a part of the support for the pivot 9 and be 110

exactly concentric therewith. For this purpose the stud is made of sheet metal with a lower edge or lips folded inward over a disk or washer 11. This washer has a threaded hole to receive the pivot 9.

It is unnecessary to refer to the electrical connections, which are made in series through the resistance coils and through the switch arm 8 in a series circuit with the transmitters, this being readily understood by those skilled in the art.

The various leading-in wires and terminals are plugged at the bottom of the instrument through knurled plugs 12 which permit of being easily removed.

What is claimed is,—

1. A telephonic transmitting appliance for deaf persons comprising a casing having a rounding edge, a transmitter concentrically disposed within said casing and providing an intervening annular cavity between the transmitter and the casing, resistance coils within said cavity and concentrically arranged around said transmitter for about a third of its periphery, and a swinging arm concentrically pivoted with

respect to said transmitter on the back of the casing adapted to cut in and cut out the various resistance coils by a movement generally parallel to said rounded edge, whereby said arm is both concealed and accessible in all positions.

2. A telephonic transmitting appliance for deaf persons, comprising a pair of transmitters, an oval casing having rounded ends and provided with annular spaces surrounding the transmitters, resistance coils in the annular space at one end, and a swinging arm on said end of the instrument on the rear face thereof adapted to cut in and cut out the various resistance coils, said arm having a handle extremity with a movement in the same arcuate direction as said rounding edge.

Signed at New York, in the county of New York and State of New York this 2nd day of April, A. D. 1912.

JOHN K. RHODES.
